A. MARCZUKOWSKI

SUPPORT FOR PORTIÈRES, CURTAINS, AND THE LIKE

Filed March 25, 1926

Inventor.
Aleksander Marczukowski

by *Heard Smith & Tenant*

Atlys

UNITED STATES PATENT OFFICE.

ALEKSANDER MARCZUKOWSKI, OF SOUTH BOSTON, MASSACHUSETTS.

SUPPORT FOR PORTIÈRES, CURTAINS, AND THE LIKE.

Application filed March 25, 1926. Serial No. 97,243.

This invention relates to a rod or support for supporting curtains, window draperies, portières and the like and particularly to that type of curtain rod which comprises a 5 tubular member divided longitudinally and having on its under side a slot through which the hanging may be inserted and a core situated within the tubular member and about which the end of the hanging passes.

10 A curtain support of this type is illustrated in my Patent No. 1,449,123, dated March 20, 1923, and the present invention has for its general object to improve the structure shown in said patent in various ways.

15 One feature of the improvement relates to a novel way of connecting the two sections of the tubular member and locking them in their operative relation. Another feature of the invention relates to a novel form of 20 core which is arranged to permit a plurality of hangings to be secured thereto and a further feature of the invention is a novel arrangement by which draperies may be supported in front of the curtain or other hanging which is hung from the core.

25 With these and other objects in view the invention comprises the various novel features which will be more fully hereinafter set forth and then pointed out in the appended claims.

In the drawings, Fig. 1 is a perspective view of a curtain rod embodying my invention;

Fig. 2 is an enlarged fragmentary perspective view showing the two sections of the tubular member opened away from each other;

Fig. 3 is an enlarged section on the line 3—3, Fig. 1 showing the curtains and draperies supported by the hanger;

Fig. 4 is a perspective view of one of the supporting brackets for the auxiliary rod 25;

Fig. 5 is an end view of the tubular member with the cap removed.

45 In the drawings the tubular member is indicated generally at 1. It is divided into two sections 2 and 3 and it is provided at its lower side with the slot 4 into which the upper end of the drapery is received. The core which is situated within the tubular member is indicated generally at 5. The particular construction of the core will be more fully hereinafter set forth.

50 The two sections 2 and 3 are connected together so that they can be opened away from

each other to expose the core and to permit a portière or hanging to be inserted all as described in the above-mentioned patent.

The means for connecting the two sections and permitting them to be opened away 60 from each other or to be closed into operative relation is somewhat similar to that shown in my above-mentioned patent and comprises a plate 6 secured to the section 2 and provided with a radial slot 8 in which 65 operates a pin 9 extending from the end of the section 3. This pin 9 is integral with and extends from a core-holding fork member 10 that is located within the tubular member and said pin extends through a boss 70 on a plate 11 secured to the end of the section 3. There is a similar construction at each end of the tubular member and the latter may be opened by sliding the pins 9 outwardly in the slots 8 and at the same time 75 turning the two sections 2 and 3 relative to each other. To assist in this turning movement the section 2 is formed with the loop 12 through which extends a hook 13 carried by the section 3 so that when pressure is 80 applied on the opposite edges of the slot 4 to separate the sections they are caused to turn relative to each other into the position shown in Fig. 2, all as shown in said patent.

85 For locking the tubular members in their operative relation I have provided two locking hooks 15 pivoted to the plates 6 and adapted to hook over the projecting ends of the pins 9. When the hooks are in place the pins are locked from moving outwardly 90 in the slots and thus the two sections are locked in their closed relation.

The ends of the rod are enclosed in removable caps 16 which have the construction illustrated in my above-mentioned patent.

95 In the present invention the core, which is indicated generally at 5, is divided longitudinally into a plurality of sections, each one of which may support a separate hanging. Three such sections are shown herein, they being indicated at 17, 18 and 19 respectively. The sections are retained in place on two pins 20 which are carried by one arm 21 of each fork 10. The other arm 22 of each fork is pivoted as shown at 23 so that it can be swung into an open position as shown by dotted lines in Fig. 2 thereby uncovering the pin 20 and allowing one or more of the core sections to be removed. When the arm 22 is 100 in its operative position shown in full lines 105 110

Fig. 2 parallel to the other arm 21 then the core sections are retained on the pin. The arm 22, therefore, constitutes a retainer.

This sectional construction of core is useful where it is desired to hang two or more curtains, one directly in front of the other. In this case, the end of one curtain 40 will be placed about one of the core sections, the end of another curtain 41 will be placed about the end of another core section, etc., each of the curtains passing into the slot 4 and round one of the core sections.

It is sometimes desirable to furnish a window with additional hangings 42 in the nature of draperies. These may be in the nature of side hangings or in the nature of valances extending across the top of the window. My present invention provides a novel construction by which such additional hangings may be supported. This structure includes an auxiliary supporting rod 25 extending parallel to the tubular rod 1 and means for supporting the auxiliary rod from the tubular rod and in such a way that the auxiliary rod may be moved forwardly in front of the main rod to support the hangings or draperies or may be moved back behind the tubular rod so that it will be behind the curtains carried by the tubular rod in case it is desired not to have any hangings supported from the auxiliary rod. This rod 25 is shown as carried by adjustable brackets 26 which are in turn secured to the tubular rod 1.

The brackets herein shown each comprises two sections 29 and 30. The section 29 presents the two parallel arms 31 and 32 connected at 33, each arm 31 having an upstanding portion 34 provided at its upper end with a hook 35 that is adapted to hook over a supporting arm 36 that is secured to the tubular member 1. The section 30 is an L-shaped section, one arm of which has a loop 37 through which the arm 31 slides or telescopes, the other arm of said section 30 being received in a socket 38 formed in a tip 39 which is secured to the auxiliary rod 25. The sliding connection between the sections 29 and 30 permits the sections 30 to be drawn outwardly to a point where the rod 25 will be supported in front of the slot 4 of the tubular member, as shown in full lines Fig. 3 and permits said sections to be retracted into the position shown in dotted lines Fig. 3 in which position the auxiliary rod 25 is placed behind the slot 4 and, therefore, behind any draperies or curtains which are hanging from the slot 4.

If it is desired to use the device for supporting draperies or valances then the bracket sections 30 will be pulled forwardly into the position shown in Fig. 3 thereby placing the auxiliary rod 25 in front of the slot 4 so that the hanging on said auxiliary rod will be situated in front of the curtains

which are supported from the tubular member 1. If it is desired not to use the auxiliary rod then the bracket sections 30 will be pushed backwardly into their retracted position shown in dotted lines Fig. 3 so that the rod 25 will be back of the slot 4 and hence back of the curtains or hangings which depend from the slot. Under these conditions the auxiliary rod 25 will be entirely hidden by the curtains and will thus present no unsightly appearance.

I claim:

1. In a device for supporting window hangings, the combination with a tubular member divided longitudinally into two separable sections, a slotted plate secured to each end of one section, a forked member carried by each end of the other section, each forked member having a shank which operates in the slot of the adjacent plate and guides the two sections as they move from open to closed position and vice versa, and a core removably secured to said forked members and about which the hanging may be folded.

2. In a device for supporting window hangings, the combination with a tubular member divided longitudinally into two separable sections, a slotted plate secured to each end of one section, a forked member carried by each end of the other section, each forked member having a shank which operates in the slot of the adjacent plate and guides the two sections as they move from open to closed position and vice versa, and a core removably secured to said forked members, said core being divided longitudinally into sections, whereby a plurality of curtains one in front of the other may be supported by said sections.

3. A device such as described in claim 1 in which each forked member has a core-holding pin extending laterally from one arm, the other arm being pivoted to allow the core to be placed on the pin or removed therefrom.

4. In a device for supporting window hangings, the combination with a tubular member divided longitudinally into two separable sections, a slotted plate secured to each end of one section, a forked member carried by each end of the other section, each forked member having a shank which operates in the slot of the adjacent plate and guides the two sections as they move from open to closed position and vice versa, a core removably secured to said forked members and about which the hanging may be folded, and locking members carried by the slotted plate and adapted to engage the shanks of the forked members thereby to lock the tubular member in its closed relation.

5. In a device for supporting curtains and window draperies, the combination with a tubular member divided longitudinally into

two separable sections, and having a slot at its under side, of a core removably retained within the tubular member and about which the hanging may be folded, an auxiliary curtain-supporting rod, and means for adjustably supporting the same from the tubular member, whereby said auxiliary rod may be adjusted into a position in front of the slot in the tubular member or in a position to the rear of the slot.

6. In a device for supporting curtains and window draperies, the combination with a tubular member divided longitudinally into

two separable sections, each having a slot in its under face, of a core retained within the tubular member and about which a hanging may be folded, an auxiliary drapery-supporting rod, and extensible brackets for supporting said rod from the tubular member, the extensibility of said brackets permitting them to be adjusted to place the auxiliary rod either in front of or at the rear of the slot in the tubular member.

In testimony whereof, I have signed my name to this specification.

ALEKSANDER MARCZUKOWSKI.
